MACHINE FOR INSERTING FASTENINGS

George Goddu, deceased, late of Winchester, Mass., by Isabelle W. Goddu, executrix, Winchester, Mass., assignor to United Shoe Machinery Corporation, Paterson, N. J., a corporation of New Jersey

Application July 28, 1932, Serial No. 625,370

14 Claims. (Cl. 1—30)

This invention relates to fastening inserting machines and is illustrated as embodied in a machine particularly adapted to insert paper pegs in the manufacture of boots and shoes.

5 A considerable number of the operations performed in the manufacture of shoes include the driving of a fastening or fastenings through one shoe part into another or through a shoe part into a last. When this operation is performed 10 by means of a machine which is not provided with a work support it has been necessary for the operator to press the work piece, which he holds in his hands, firmly against the nozzle or other fastening guide of the machine. This is 15 laborious since the operator is forced to sustain the impact of the blow and, by reason of his failure to exert sufficient pressure, often results in poor work by reason of the layers through which the fastenings are inserted not being 20 squeezed closely together. A well-known operation, which may be used to illustrate an example of this difficulty, is McKay sole laying, that is the preliminary attachment of soles to McKay 25 shoes by fastenings driven through the soles into the lasted upper and insole. It is often found that, by reason of failure of the operator to press the lasted shoe with sufficient force against the 30 nozzle of the fastening inserting machine, the fastenings, though they hold the sole in place in the shoe bottom, nevertheless permit the outsole to gape from the upper and insole thereby interfering with the proper performance of the subsequent through-and-through stitching operations 35 by which the soles are permanently attached.

It is accordingly an object of this invention to 40 provide an improved machine by which the layers of a work piece will be forced together by a hammer-blow substantially at the instant of the start of the driving of the fastening whereby, even in the absence of a work support, the fastenings will hold the layers in close engagement with each other.

In accordance with this object a feature of 45 the invention resides in a fastening inserting machine having means for inserting fastenings in a work piece, a member through which a fastening is inserted into the work, and means including a lever arranged to move said member against the work to impart a hammer blow to the work immediately prior to the insertion of a 50 fastening.

The illustrated machine is also provided, in accordance with another feature of the invention, with means for maintaining the nozzle in 55 a position toward the work until after the fas-

tening receiving hole has been formed in the work. The means is illustrated herein as a latch arranged to engage the connection between the bell crank lever to maintain the nozzle in its position toward the work.

While the invention is illustrated herein as embodied in a fastening inserting machine particularly adapted to drive fibre pegs into the sole portions of shoes, it should be noted that the invention is not limited in its utility to such use or to embodiment in fastening inserting machines of the type illustrated and, accordingly, the construction disclosed herein should be regarded as merely one example of the forms in which this invention may be embodied.

With the above and other objects in view the invention will now be described with reference to the accompanying drawings and pointed out in the claims.

In the drawings,

Fig. 1 is a side elevation of the head of a fastening inserting machine embodying this invention;

Fig. 2 is a detail view of the clutch mechanism for stopping and starting the machine;

Fig. 3 is a sectional view taken along the line III—III of Fig. 1, showing on an enlarged scale the nozzle reciprocating mechanism;

Fig. 4 is a cross sectional view taken through the shank portion of a lasted shoe after one side of the sole has been temporarily secured; and

Fig. 5 is a view similar to Fig. 4 but showing both sides of the sole temporarily secured to the shoe.

The machine is provided with a head 12 in which the operating instrumentalities of the machine are mounted. The head 12 is mounted on a column 14 which is made up of two telescoping and relatively adjustable sections (not shown). An electric motor is mounted in the column and connected to a shaft (not shown) housed in the column, which in turn is connected to a friction clutch. The clutch is secured to one end of a shaft 16 on which is mounted a group of cams preferably formed as a unit and hereinafter designated as a cam member indicated generally by the reference character 18. A spring 20 normally urges the adjacent surface of the clutch member 22 rearwardly into engagement with the clutch member connected to the shaft in the column.

The clutch member 22 is provided with a collar 24. The collar or hub 24 is provided with a pair of pins 25 on opposite sides of the shaft 16 engaging hooks formed in the upper end of a lever

26 fulcrumed at 28 to the head of the machine. Thus the lever 26 can be held in position to compress the spring 29 to maintain the clutch member 24 in its forward or non-power transmitting position while, when the lever 26 is rocked by mechanism, hereinafter described through a treadle rod 30 in a clockwise direction, the clutch member 22 is moved rearwardly by the force of the spring 29 into engagement with the 10 constantly driven clutch member and thus becomes effective to transmit power to the cam member 18.

The machine is provided with a single tool 32 arranged to operate both as an awl and as a 15 driver. The tool 32 is clamped to a tool carrier mounted for vertical reciprocation in a guideway carried by or formed in the head 12 of the machine.

The mechanism for giving the tool 32 its awl 20 stroke and its driver stroke includes a lever 34 fulcrumed at 36 to the head of the machine and having two parallel arms pivoted at their rear ends to a link 38 positioned approximately vertically and ending at its lower end in a slot 40 25 formed in a rearwardly extending arm of a bell crank lever 42 fulcrumed at 44 to the head of the machine and having an upwardly extending arm 46 carrying a cam roll 48 positioned in a cam track 50 formed in the cam member 18. The slot 30 40 is formed on an arc of a circle having a radius equal to the distance between the pivots of the arm 38 and positioned concentric with the pivotal connection between the link 38 and the lever 34 at the time of the driver stroke of the tool 32. 35 The form of a cam track 50 is such as to position the lever 34 in its uppermost position early in the cycle of operation when the tool 32 is acting as an awl and to position the lever 34 in its lowermost position later in the cycle when the 40 tool is operating as a driver.

Fulcrumed at 52 to the lever 34 is another lever 54 which is provided at its forward end with teeth (not shown) entering the openings 45 between corresponding teeth formed in the upper end of the tool carrier. A stiff coil spring surrounds the fulcrum 52 of the lever 54 and is anchored at one end to a disk 56 which is adjustably secured to the lever 34 by a pin 58. The other end of the spring is secured to or formed as a part of the lever 54. The spring thus tends at all times to rotate the lever 54 in a counter-clockwise direction, as viewed in Fig. 1, and to urge the tool carrier and the tool 32 downwardly.

55 At its forward end the cam member 18 is provided with a lifting cam 60 having a pair of elevated portions (not shown). Mounted for vertical sliding movement in the head 12 of the machine is a lifting bar 62, the lower end of which bears against the lifting cam 60 and thus serves as a lifting block. The bar 62 is provided with a block (not shown) which is positioned in a slot 60 formed in the lever 54. Thus, as the cam member 60 rotates, the lifting bar 62 is elevated by the cam, the lever 54 being rocked upwardly. Then when one elevated portion of the cam 60 passes out from beneath the end of the lifting bar 62 the spring above referred to forces the lifting bar downwardly, thus rocking the forward end of the lever 54 downwardly in a counterclockwise direction, as shown in Fig. 1, and forcing the tool 32 downwardly. The first downward movement of the tool 32 occurs when the fulcrum 52 of the lever 54 is in its uppermost position, the tool 32 70 then being forced downwardly through a nozzle 75

64 and into the work to form a fastening receiving hole. When the shaft 16 has been rotated another 180° and the upper elevated portion of the cam 60 has raised the tool 32 and passed out from beneath the lifting bar 62 the fulcrum 52 of the lever 54 has been moved to its lowermost position. Thus, the downward movement of the tool 32 is only sufficient to drive the fastening which at that time has been brought into alignment with the throat opening of the nozzle 64 10 and with the tool 32.

In order to permit the machine to be used to drive fastenings of either of two lengths as may be desired, for example, in McKay sole laying where it is preferable to use shorter fastenings to 15 secure the forepart of the sole than are used in the heel seat, the machine is provided with mechanism for varying the position of the lever 34 and the fulcrum 52 of the lever 54 at the time of the awl stroke of the tool 32. For this purpose the 20 link 38 is pivotally connected somewhat above its lower end to a link 66 pivoted at its other end to an approximately vertical lever 68 fulcrumed at 44 to the head of the machine and having its lower end connected by a link 72 to a bell crank 25 lever 74 fulcrumed at 76 to the head of the machine and urged in a counterclockwise direction by a spring (not shown). The bell crank lever 74 has a rearwardly extending arm connected by an adjustable rod 80 to a treadle mounted in the 30 base of the machine and arranged by its displacement to move the rod 89 downwardly thus rocking the bell crank lever 74 and the lever 68 in a clockwise direction as viewed in Fig. 1 against the action of the spring 78 and moving the lower 35 end of the link 38 rearwardly in the slot 40 of the lever 42. Thus, when the operator steps on the treadle the amplitude of the rocking movement of the lever 34 above its fulcrum 36 is greater than when the treadle is in its normal position. The fulcrum 52 of the lever 54 is, accordingly, raised to a greater extent at the time of the awl stroke of the tool 32 if the treadle is displaced and the forward end of the lever 54 is correspondingly lowered to a greater extent at the 40 time of the awl stroke of the tool 32 so that a deeper hole is made in the work piece presented to the nozzle 64.

In order definitely to determine the depth of the holes formed in the work depending upon 50 whether the treadle is elevated or depressed the bell crank lever 74 is provided with a slot 82 in which is carried a pair of adjustable stops 84, 86 clamped in desired position by screws 88, 90. A stationary pin 92 carried by the head 12 of the 55 machine is engaged by one or the other of the stops and thus controls the upper position of the treadle and the extent to which the treadle can be displaced. Conveniently a scale is carried by the lever 74 to aid in the proper position- 60 ing of the stops 84, 86.

The illustrated machine is arranged to be started by a downward movement of the treadle rod 30 which is connected at its lower end to a second treadle (not shown) and at its upper end to an 65 arm 93 of a bell crank lever 94 fulcrumed at 96 in the head of the machine. The arm 93 and the treadle rod 30 are moved upwardly by a spring 78 connected at one end to the machine frame and at its other end to the lever 93. The fulcrum 96 is in the form of a shaft and has secured at its other end an arm 99. The arm 99 engages a pin 101 secured to a trip lever 100 which is mounted on the shaft 96 and is rotatable thereon. The free end of the trip lever 100 is provided with a 75

notch or recess into which fits the lower end of the other arm of the bell crank lever 102. The bell crank lever 102 is pivoted to the lower end of the lever 26 and has a forwardly extending arm which is pivoted to a link 104 connected to a sliding member 105. The sliding member 105 is mounted for forward and rearward movement and has a cam roll which rides in a cam path 50 formed in the cam member 18. Surrounding the shaft 96 is a torsion spring 103, one end of which bears against the pin 101 and the other end bears against the frame of the machine, thereby causing the trip lever 100 normally to be urged upwardly into engagement with the lower arm of the bell crank lever 102. When the machine is brought to a stop, the toggle formed by the arm 102 and the link 104 is partly broken and is held in this condition by the engagement of the lower arm of the bell crank lever by the notch formed in the hooked end of the trip lever 100. This holds the lever 26 securely in the position shown in Fig. 2 with the spring 20 under compression and the clutch member 22 in non-power transmitting position. When the treadle rod 30 is moved downwardly the bell crank lever 94 is rocked about its fulcrum 96 thus moving the trip lever 100 downwardly to an extent sufficient to release the lower arm of the bell crank 102 from the notch in the latched or hooked end 100, the lower end of the lever moving to the right along an arcuate surface formed on the arm 98 as a toggle formed by the arm 102 and the link 104 breaks completely under the pressure applied to the upper end of the arm 26 by the spring 20. Thus the clutch member 22 is moved rearwardly by the spring 20 to power transmitting position and the machine starts. In order to stop the machine at the end of each cycle of operation the sliding member 105 to which the link 104 is connected moves forwardly and straightens the toggle 102, 104 so that when later in the cycle the movable member 105 is moved rearwardly by the cam 50 the lower end of the lever 26 is moved to the left. At the same time the lower end of the bell crank lever 102 enters the notch formed in the hooked end 100 of the bell crank lever arm 98 thus leaving the parts in the condition shown in Fig. 2.

The mechanism for feeding paper twine 116, from which the fibre pegs 117 inserted by the machine are formed, is not described herein since any well-known form of feeding mechanism may be used. The twine is fed through a tube 118 into a passage formed in a transfer bar 120. The transfer bar 120 is provided with a cam roll 122 positioned in a cam track 124 formed in the cam member 18. Thus after the tool 32 has completed its work penetrating stroke and has been returned to substantially its original position the transfer bar 120 is moved forwardly cutting a fastening of proper length from the twine and moving the peg so formed into alignment with the path of movement of the tool 32. The lever 34 in the meantime has been moved downwardly, thereby shifting fulcrum 52 of the lever 54, and the cam 60 raising the lever 54 about its fulcrum 52, bringing the tool 32 into position to drive the fastening in the passage in the transfer bar 120.

In operating upon certain types of shoes, for example McKay shoes, it is desirable to lay the sole prior to permanently securing the sole in position on the shoe by stitches or other fastenings. Ordinarily a number of spaced fastenings are driven through the outsole and into the over-lasted margin of the upper and insole. When

paper pegs are used for this purpose it is sometimes difficult to bring the edge of the outsole, particularly at the shank portion of the shoe, close against the adjacent portion of the upper.

The illustrated machine has been provided with means for bringing the edge of the sole close to the adjacent portion of the shoe upper and, as illustrated, the nozzle 64, which is slidably mounted in the head of the machine, is provided with means to impart a hammer blow to the work just prior to the insertion of a fastening. The forward portion of the nozzle 64 is provided with a plurality of teeth 126 which engage teeth 128 formed on one arm of a bell crank lever 130 fulcrumed at 132 to the head 12 of the machine. The other arm of the bell crank lever 130 is provided with an adjusting screw 134 which is locked in adjusted position by a lock nut 136. The end of the adjusting screw 134 engages a sliding bar 136 which is mounted for movement in holes 20 formed in the head of the machine. The transfer bar 120 at its rear end is provided with a laterally projecting lug 138 which is arranged upon movement of the transfer bar 120 to feed a fastening into the line of drive of the tool 32 to engage the end of the slideable bar 136, thereby moving the bell crank lever 130 in a clockwise direction. The transfer bar 120 moves at a comparatively high rate of speed which is sufficient to move the nozzle 64 approximately one-eighth of an inch and, because of the speed of movement of the nozzle 64, a hammer blow is imparted to the work which will bring the edge of an outsole 140 close against the adjacent portion of an upper 142 of a lasted shoe. As shown in Fig. 4 of the drawings one edge of the outsole has not been secured and it would, perhaps, be difficult to secure the other edge of the outsole 140 against the upper 142 of a lasted shoe. But the hammer-like blow imparted to the nozzle 64 strikes the outsole 140 and brings it into close engagement with the bottom of the shoe. It should be noted at this point that, although a substantial blow is given to the work, the inertia of the lasted shoe will counteract the blow delivered by the nozzle 64.

When the nozzle 64 is in its upper position the tool 32, particularly at the conclusion of the hole forming operation of the tool 32 would project too far beyond the end of the nozzle, thereby moving the work away from the nozzle which might in some cases result in improper alignment of the hole in the shoe with the fastening to be inserted in that hole. It is desirable, therefore, to provide means for maintaining the nozzle in its lower position until just before a hammer blow is imparted to the work. The sliding bar 136 is provided with a notched portion 144 into which is fitted a latch 146 fulcrumed at 148 to a plate 150 secured to the machine head 12 by screws 152. Secured to the pin forming the fulcrum 148 is a lever 154 arranged to be engaged by a spring trip 156 which is secured to the bell crank lever 42 by a machine screw 158. The latch 144 is normally urged downwardly by a spring 160. When the bell crank lever 42 is swung in a clockwise direction as viewed in Fig. 1 the spring trip 156 moves upwardly raising the end of the latch 144 out of the recess 144 thereby permitting the sliding bar 136 to be moved toward the right under the influence of a torsion spring 162 which is secured to the fulcrum of the bell crank lever 130. The nozzle 64 is, therefore, maintained in its lower position until just prior to the hammer stroke.

While the operation of the various parts of the machine has already been described, it may be

helpful now to consider the operation of the machine as a whole. With the parts of the machine in position shown in Fig. 1, the work in which the fastenings are to be inserted (for example, a lasted McKay shoe to which the outsole 140 is to be preliminarily attached or "laid") is presented by the operator to the nozzle 64. The operator then trips the clutch by rocking the lever 93 in a clockwise direction, as shown in Fig. 1, thereby permitting the toggle 102, 104 to be broken under the influence of the spring 20. The spring 20 thus moves the clutch member 22 to the left into power transmitting position and the cam member 18 begins to rotate. During the early part of the cycle the nozzle 64 is maintained in the position shown in Fig. 1 and the tool 32 is driven down and passes through the lower end of the nozzle 64 to form a hole in the work. Then the lifting bar 62 and the tool 32 are lifted by an elevated portion of the lifting cam 60, the lever 34 at the same time being rocked about its fulcrum 36 to lower the fulcrum 52 of the lever 54 so that the next stroke of the tool 32 will serve as a driving stroke. At the same time the strip of fastening material 116 is fed downwardly an appropriate distance. When the fulcrum 52 of the lever 54 is shifted by rotation of the bell crank lever 42 the spring trip 156 engages the lever 154, moving the latch out of the recess in the sliding bar 136. The shear member or transfer bar 120 then moves forwardly to sever a fastening and to bring the passage therein into alignment with the tool 32 in the opening of the nozzle 62. At the same time the nozzle 64 is driven against the work by the mechanism described above. As the transfer bar or shear member 120 moves forwardly the toggle 102, 104 is straightened so that as the rod 105 moves rearwardly after the fastening has been driven the lever 26 will be rocked about its fulcrum compressing the spring 20 and moving the clutch member 22 into non-driving position. As the lever 26 is thus rocked, the lower end of the lever is caught in the notch formed in the hooked end 100 of the bell crank lever 98 so that the machine comes to rest with the toggle latched in a partly broken condition, as shown in Fig. 2.

Having thus described the invention, what is claimed as new and desired to be secured by Letters Patent of the United States is:

1. In a fastening inserting machine, means for inserting fastenings in a work piece, a member through which a fastening is inserted into the work, and means including a lever arranged to move said member against the work to impart a hammer blow to the work immediately prior to the insertion of a fastening.

2. In a fastening inserting machine, a tool for forming a fastening receiving hole in a work piece and for inserting a fastening in said hole, a transfer bar constructed and arranged to sever a fastening from a strip of fastening material and to move said fastening into the path of movement of said tool, a nozzle arranged for movement toward and from the work, and connections between said nozzle and said transfer bar constructed and arranged to impart a hammer blow to the work prior to the insertion of the fastening in the work.

3. In a fastening inserting machine, means for inserting fastenings in a work piece as the work is held in the hands of an operator, a member having a passage through which a fastening is inserted into the work, and means including a bell crank lever for moving said member against

the work to impart a hammer blow to the work immediately prior to the insertion of the fastening.

4. In a fastening inserting machine, means for inserting fastenings in a work piece, a member for moving a fastening into the path of movement of the inserting means, a second member having a passage through which the fastening is inserted into the work, and means including lever connections between said members for moving the second member against the work to impart a hammer blow to the work immediately prior to the insertion of a fastening. 5

5. In a fastening inserting machine, means for inserting fastenings in a work piece, a member for moving a fastening into the path of movement of the inserting means, a member having a passage through which the fastening is inserted into the work, and means including a bell crank lever connected to said first-mentioned member 15 and to said last-mentioned member for moving said member against the work to impart a hammer blow to the work prior to the insertion of a fastening. 20

6. In a fastening inserting machine, means for 25 inserting fastenings in a work piece, a device for moving a fastening into the path of movement of the inserting means, a movable member having a passage through which the fastening is inserted into the work, and a bell crank lever connected to said device and constructed and arranged to move said member against the work to impart a hammer blow to the work prior to the insertion of a fastening. 30

7. In a fastening inserting machine, a tool for 35 forming a fastening receiving hole in a work piece and for inserting a fastening in said hole, a transfer bar constructed and arranged to sever a fastening from a strip of fastening material and to move said fastening into the path of 40 movement of said tool, a nozzle arranged for movement toward and from the work, and connections between said nozzle and said transfer bar including a bell crank lever and a sliding bar constructed and arranged to impart a hammer 45 blow to the work prior to the insertion of a fastening in said fastening receiving hole.

8. In a fastening inserting machine, a tool for forming a fastening receiving hole in the work piece and for inserting a fastening in said hole, 50 a transfer bar having a passage therein for receiving a fastening and for moving the fastening into fastening inserting position, a member arranged for movement toward a work piece to impart a hammer blow to the work piece prior 55 to the insertion of the fastening, and means for holding the member toward the work during the hole forming operation.

9. In a fastening inserting machine, a tool for forming a fastening receiving hole in a work piece 60 and for inserting a fastening in said hole, a transfer bar for moving a fastening into the path of movement of said tool when said tool is operating as a driver, a nozzle movable toward the work to impart a hammer blow to the work, a bell 65 crank lever connected to said nozzle, and means connecting said transfer bar and said lever whereby movement of the transfer bar is transmitted to the nozzle to impart a hammer blow to the work prior to the insertion of a fastening 70 in said fastening receiving hole.

10. In a fastening inserting machine, a driver for inserting a fastening in a work piece, means for severing and feeding a fastening into the path of movement of the driver, a member hav- 75

ing a passage therein through which the driver moves to insert a fastening in the work piece, and means including a geared connection between said severing means and said member for 5 moving said member toward the work to impart a hammer blow to the work prior to the fastening inserting operation.

11. In a fastening inserting machine, a reciprocable tool for forming a fastening receiving hole in the work piece and for inserting a fastening in said hole, a transfer bar having a passage therein for severing a fastening from a strip of fastening material and for feeding the severed fastening into the path of movement of the tool, 10 a nozzle having a driver passage therein, teeth on said nozzle, a bell crank lever, teeth on the bell crank lever meshing with the teeth on the nozzle, and means connecting said transfer bar and said bell crank lever to impart movement to said nozzle prior to the insertion of a fastening in the work.

12. In a fastening inserting machine, a reciprocable tool for forming a fastening receiving hole in the work piece and for inserting a fastening in said hole, a transfer bar having a passage therein for severing a fastening from a strip of fastening material and for feeding the severed fastening into the path of movement of the tool, 15 a nozzle having a driver passage therein, teeth on said nozzle, a bell crank lever, teeth on the bell crank lever meshing with the teeth on the nozzle, means connecting said transfer bar and said bell crank lever to impart movement to said nozzle prior to the insertion of a fastening in the work, and means for maintaining the nozzle in its position toward the work during the hole forming operation.

13. In a fastening inserting machine, a reciprocable tool for forming a fastening receiving

hole in the work piece and for inserting a fastening in said hole, a transfer bar having a passage therein for severing a fastening from a strip of fastening material and for feeding the severed fastening into the path of movement of the tool, 5 a nozzle having a driver passage therein, teeth on said nozzle, a bell crank lever, teeth on the bell crank lever meshing with the teeth on the nozzle, means connecting said transfer bar and said bell crank lever to impart movement to said nozzle prior to the insertion of a fastening in the work, a latch arranged to engage the connection between the bell crank lever and the transfer bar to maintain the nozzle in its position toward the work, and means constructed and arranged to 10 release the latch after a fastening receiving hole has been formed in the work piece.

14. In a fastening inserting machine, a reciprocable tool for forming a fastening receiving hole in the work piece and for inserting a fastening in said hole, a transfer bar having a passage therein for severing a fastening from a strip of fastening material and for feeding the severed fastening into the path of movement of the tool, 15 a nozzle having a driver passage therein, teeth on said nozzle, a bell crank lever, means normally urging the nozzle away from the work, teeth on the bell crank lever meshing with the teeth on the nozzle, means connecting said transfer bar and said bell crank lever to impart movement to said nozzle prior to the insertion of a fastening into the work, a latch for maintaining the nozzle in position toward the work, and means constructed and arranged to release the latch 20 after a fastening receiving hole has been formed 25 in the work piece.

ISABELLE W. GODDU,
Executrix of the Will of George Goddu, Deceased.
